UNITED STATES PATENT OFFICE.

PAUL MENZEL, OF VIENNA, AUSTRIA-HUNGARY.

TUBE-MAKING MACHINE.

1,170,837.

Specification of Letters Patent.

Patented Feb. 8, 1916.

Application filed November 26, 1913. Serial No. 803,103.

To all whom it may concern:

Be it known that I, PAUL MENZEL, a subject of the Emperor of Austria-Hungary, residing at Strauchgasse 1, Vienna, Austria-Hungary, have invented certain new and useful Improvements in Tube-Making Machines, of which the following is a specification.

The object of this invention is a machine for carrying out the method for the production of a tube set forth in an application for Letters Patent Serial No. 803,051 filed by me Nov. 25, 1913.

The drawing gives an illustration of the machine forming the subject matter of this invention.

Figure 1 is a front view: Fig. 2 is a plan view: Fig. 3 is a view of part of the machine on an enlarged scale: Fig. 4 is a vertical section on A—B Fig. 3, seen in the direction of the arrow X: Fig. 5 illustrates details.

The top edges 2 of the two lateral walls 1 of the frame of the machine are dovetailed in cross section so as to provide a guide for each of the supports 3 which are capable of sliding horizontally in the longitudinal direction of the machine. The base of each support 3 has a groove underneath in which the respective dovetails 2 fit. Under the lower surface of each dovetail a rack 8 is arranged. The two supports 3 carry a horizontal shaft 4. The shaft 4 passes through horizontal longitudinal apertures 5 provided in both the lateral walls 1 of the frame and is furnished at the front with a crank 6 and carries two spurwheels 7 each of which engages one of the racks 8 so that upon the crank 6 being rotated the spurwheels 7 are simultaneously driven along the racks 8 so as to impart to the supports 3 an equal progressive motion. Each support 3 carries a bearing 9 into which one end of a hollow drum 10 can be inserted and be capable of rotating freely. Said drum 10 serves as a mandrel to wind up the band 102 from which the insulating tube is to be made. The length of the drum 10 depends upon the width of the band used. The latter should preferably be made of paper which, for practical purposes, should not exceed three meters in width. The bearings 9 are divided in their vertical longitudinal plane. One

half 9^A of each said two bearings is rigidly connected with the corresponding support 3 while the other corresponding half 9^B is capable of being swung around the horizontal pivot 11. To each half bearing 9^A a screw 13 is hinged by means of a horizontal pin 12. The screw 13 passes between two lugs 14 on the corresponding bearing half 9^B and can be secured by means of a nut 15 furnished with a handle. In this manner both bearings 9 may, for the purpose of laterally removing the drum 10, be opened and after the introduction of the latter, be again closed up and fastened. A pulley 16 is keyed to the projecting front end of the drum 10 and causes it to rotate when actuated by the operator's hand which may be used instead of the belt 31. The back support 3 is furnished with a catch 17 extending downward between the two projections 18 and 19. The latter are formed like collars and secured in an adjustable manner to a horizontal cylindrical rail 20 which is longitudinally displaceable in bearings 21 which are fixed to the back lateral wall 1 of the frame of the machine. The support 3 when moved to and fro by means of the catch 17 displaces the rail 20 in opposite directions according as to whether the catch 17 strikes the collar 18 or the collar 19. The object of this transmission of movement by means of the support 3 upon the rail 20 will be explained later on.

The back support 3 carries a bracket 21 (Fig. 5) in which a vertical screwed spindle 23 is fixed in such manner that it can be turned but cannot be displaced axially. The upper end of the screwed spindle is furnished with a hand wheel 22. A nut 24 engages with the spindle 23 but is itself incapable of rotary motion so that upon the spindle 23 being rotated, the nut moves longitudinally on the spindle. The nut 24 is rigidly connected with the bent arm 25 and a horizontal pin 26 loosely carries a two-armed lever 27. A spiral spring 29 which holds one of the arms tends to push the other arm of the lever 27 provided with a roller 28 against an insulated contact piece 30 carried by the bent arm 25. The lever 27 which is made of conducting material is connected with one of the poles of a source of electricity and the contact piece 30 with

the other pole. Within the circuit of the source of electricity an electro-magnetic coupling is arranged which switches off the driving gear between the continuously working motor and the drum rotated by the motor through the belt 31 and the pulley 16 so as to break off the current. As the support 3 moves away with the drum 10 whereby the distance of the same from the driving gear previously mentioned, is altered, the belt 31 must be furnished with some automatic stretching device. The electro-magnetic coupling of the transmission gear of the motor and the automatic belt stretching device are of known type and for the sake of simplicity are not shown in the drawings. So soon as the tube wound around the drum 10 has reached the desired outer diameter, the roller 28 comes in contact with the circumference of the tube, is raised and shifts the lever 27 whereby the latter ceases to remain in contact with the contact 30. The result is that the transmission gear which actuates the rotation of the drum 10 as explained above is automatically switched off. Upon the nut 24 being fixed at the required height by means of the spindle 23 and the hand wheel 22 this device can be so arranged beforehand that the action of the motor on the drum 10 is automatically stopped so soon as the wound up tube has reached the desired thickness.

The progressing motion of the supports 3 and of the drum 10 which it carries is limited in one direction (according to Fig. 1 of the drawings, to the right) by a couple of supporting rollers 32 and 33 arranged one above the other at a distance apart, and in the other direction by a pair of special bearings 34 the construction and purpose of which will be explained later on.

The hollow cylindrical and heatable rollers 32 and 33, the horizontal parallel hollow shafts 35 and 36 of which lie in a vertical plane at right angles to the longitudinal direction of the machine, that is to the direction of motion of the band, are as long as the greatest width of said band which can be wound upon the drum 10 with this machine. The shaft 35 is carried at each end by a guide 37 and the shaft 36 is also carried at each end by a guide 38. Each of the two guides 37 and 38 lying the one above the other can slide on the part 39 which is provided on one of the standards 40 carried by the frame of the machine. A spindle 41 is screwed into each two opposing guides 37 and 38 and the guides, like the parts of the respective spindle 41 which coöperate with them, are furnished with opposite screw-threads. Both the threads of each spindle 41 are separated by a collar 42 forming a projection. The upper end of each of the spindles 41 placed in the corresponding

standard 40 is furnished with a wheel 43 by the rotation of which the distance between the two upper and lower pairs of guides 37 and 38 can be varied. In this way the distance between the two cylinders 32 and 33 may be regulated beforehand according to the required thickness of the tubing wound around the drum 10.

On each longitudinal side of the machine one of the two bearings 34 previously referred to, is disposed in such manner that the distance between these bearings is less than the distance between the bearings 9 carried by the support 3. The longitudinal center of the bearings 34 lies in the same horizontal plane as the longitudinal center of the bearings 9. Both the cheeks 34^A of each bearing 34 are furnished with horizontal arms 34^B made of resilient material which arms are secured to a small bracket 44 firmly fixed to the frame of the machine. The longitudinal edges of the cheeks 34^A are bent in such manner that they diverge from one another (Figs. 1 and 3). The distance between the two arms 34^B of each bearing 34 may be altered and adjusted by a screw 45 furnished with a handle, whereby the two corresponding cheeks 34^B may be fastened together more or less tightly. The two small brackets 44 carry a board 48 movable around a horizontal shaft 46 and provided with a counterweight 47 which by over-balancing falls upon the wound up drum 10 when the latter is supported by the two bearings 34. Within the space inclosed by the frame of the machine a horizontal narrow table 49 is arranged so as to be capable of an up and down motion. The length of the table measured in the direction of the width of the machine is at least equal to the greatest width of the band capable of being wound upon the drum 10 by this machine. The position of the table 49 relatively to the motion of the support is so calculated that the central line of the drum 10 occupies a position somewhat above the longitudinal center of the table 49 when the support 3 has performed half the distance from one end toward the other end of its journey. The narrow sides of the table 49 each engage a vertical guide 50 which is rigidly connected with the wall 1 of the frame of the machine next to it. The two guides 50 are provided with horizontal longitudinal slits 51 which with the previously mentioned slits 5 permit of introduction of the shaft 4 and said guides are connected together and supported at their upper ends by a horizontal rod 52. The table 49 is supported by two stands 53 which are provided near the narrow ends of the plate 49. Each stand 53 is placed inside a hollow post 54 in which it can be raised or lowered as required. The lower end of each stand 53 is formed into a rack 55 which is

engaged by a spur-wheel 57 through a vertical longitudinal slit 56 provided in the side of the post 54. The two spur wheels 57 have a common shaft 58 the ends of which are 5 free and rotate in each of the bearings 59, carried by the respective posts 54. The front end of the shaft 58 is furnished with a chain wheel 60. The smooth upper part of each stand 53 which projects from the post 54 is 10 furnished with a collar 61 and above the same an adjustable collar 62 is provided. Between the collar 61 and the collar 62 a guide 63 displaceable within fixed limits is 15 arranged, which guide has a horizontal lateral projecting trunnion 64. Said trunnion engages a longitudinal slit 65 of a lever which is secured to a horizontal shaft 67 across the frame of the machine. This shaft is common to both levers 66 and provided 20 with a crank 68 at the front end. A lever 70 loaded with a counterweight 69 is attached to the shaft 67 about the middle.

The lower end of a vertical plate spring 71 is secured to the guide 63. The length of 25 said plate spring, measured in the direction of the width of the machine, corresponds to the length of the rollers 82 and 83. The free upper edge of the spring 71 is furnished with a row of rectangular tongues 73 of 30 equal size, and equally spaced apart so as to form recesses 72 between each two adjacent tongues (Fig. 4). The upper ends of the lugs 73 are formed in such manner that they provide bearings for a shaft 74 which extends 35 over the whole length of the spring 71 parallelly to the central line of the drum 10. Free rotatable small rollers 75 rest upon said shaft, each of which passes through one of the notches 72. The spring 71 passes 40 through a vertical slit 76 which extends over the whole length of the table 49. The lower part of the slit 76 is narrower than the diameter of the small rollers 75 so that it prevents the latter from passing 45 through downward. The upper part of the slit 76 on the contrary is wider so that the small rollers 75 find their position in it and can thus be raised from the slit and reach above the table 49. The passage between 50 these two different dimensioned parts of the slit 76 is provided with a constriction which can serve as a support for the small rollers 75.

The upper part of the table 49 carries a 55 pair of cutters 77 arranged at a distance from one another the cutting line of which lies vertically to the direction of motion of the band and extends over the whole width of the table 49. Both cutters 77 form together with another cutter (not shown in the drawing) which passes between them, when so actuated, a paper cutting device. This secondly mentioned cutter may, for instance, consist of a cutting wire stretched obliquely

over the whole width of the machine in a vertical plane, and driven through the aperture between the cutters 77.

A transferring device is arranged upon the frame of the machine. Said device consists of two hollow parallel cylinders 78 and 79 arranged with a space between them and which extend over the whole width of the machine and are secured upon two horizontal hollow shafts 80 and 81 at the same height. Each end of the shafts 80 and 81 carries respectively chain wheels 82 and 83. An endless crossed chain 84 is fitted on the two wheels 82 and 83. The shaft 80 carries furthermore a pulley 85 which is continuously actuated by the belt 86 so that the rollers 78 and 79 are made to rotate in opposite directions. Between the rollers 78 and 79 parallel to the same a smaller roller 87 is arranged which freely rotates upon its stationary shaft 88. The roller 87 which also extends over the whole width of the machine is in contact with the roller 79 only, so that it is set in motion by the latter in an opposite direction. Roller 78 is immersed in a trough 89 which contains the liquid insulating material to be transferred to the band 102. In order to keep said material in a liquid state, heating pipes are arranged in the double wall 90 of the trough 89. In trough 89 a mixer 91 is provided for the purpose of agitating the material. The cylinder 78 drives by its rotation the liquid material from the trough 89 on to the roller 87. Above the latter a channel 92 in the form of a groove which extends over the whole length of the roller is provided, which allows part of the material to pass from the roller 87 to the roller 79 while the excess runs off through apertures into the groove 92 and through outlet pipes connected therewith into the trough 89. By adjusting the distance of channel 92 from roller 87, a sufficiently thick and even coating of insulating material may be applied to roller 79, the thickness of the coating to be applied to the band 102 being controlled as hereinafter stated.

Underneath the transferring device provision is made for a roller 93 which extends over the whole width of the machine, and is carried by two levers 94, which are both rigidly connected to a horizontal shaft 95 rotatably mounted in a bearing on the base of frame 96. One of these two levers 94 is connected with rail 20 already mentioned by means of an articulated rod 97. Underneath the front standard 40 in the frame of the machine, a handwheel 98 is provided to the shaft of which a chain wheel 99 is connected. An endless chain 100 is passed over the two wheels 60 and 99. Between the transferring roller 79 and the supporting roller 83 a conveyor 101 for the band 102 traversed by

heating pipes, is arranged in an oblique upward direction. Near the frame of the machine, two stands 103 are provided which serve to support a reel 104 of paper to be wound. The shaft supporting the latter carries a brake band 105 one end of which is secured to the front support 103 and the other end of which is loaded with a weight 106. The weight 106 is supported by one arm of an angular lever 108 movable around the horizontal pin 107 while the other arm is connected with a pulling rod 109 which extends to the opposite end of the frame of the machine. The base of the stand 96 carries, on the side facing the reel 104 a bracket 110 which supports a roller 111 extending over the whole width of the machine, to guide the band 102 unrolled from the reel 104.

104.
20 The production of the tubing by means of the above described machine, is carried out as follows: In the first place the distance between the two supporting rollers 32 and 33 is adjusted by means of the two screw spindles 41 and the height of the nut 24 of the self-adjusting device (Fig. 5) which corresponds to the required outer diameter of the tube to be wound up around the drum 10 between the rollers 32 and 33 is adjusted by 25 means of the screw spindle 23. Furthermore, the projection or collar 19 must be so adjusted that when the support 3 is shifted away for the first time from the cylinders 32 and 33 against the bearings 34 it must not be actuated by the catch 17 so that the 30 guiding roller 93 should reach the height shown in Fig. 1 and the band 102 be applied to the transferring roller 79. Then the drum is introduced into the bearings 9 which are 35 previously opened and then closed again, and shifted together with the support 3 by means of the crank 6 to the central position occupied by the drum 10 above the longitudinal central line of the table 49. If desired, 40 the drum may be coated with an insulating substance which has for its object, to facilitate the stripping of the tube from the drum after the latter has been heated, while the insulating substance will also form a film on 45 the inner face of the completed tube. When the roller 104 is introduced into the bearings of the support 103 the free end of the band 102 is then appropriately seized by tongs and the band, upon the action of the brake 105 50 being at the same time reduced, is drawn over the guiding rollers 111 and 93 and the guide 101 between the supporting rollers 32 and 33 and takes its position upon the drum 10 in such manner that a part of the band 55 55 projects over the drum. Then by means of the roller 79 the insulating material is transferred in the desired thickness on to the progressing band. The thickness of the layers of the insulating substance applied thus 60

depends upon the height of the guiding roller 93 and also upon the more or less close approximation of the latter to the transferring cylinder 79. Now by an approximate rotation of the spur wheel 57 by means of the hand wheel 98 and the chain gear 99, 100 and 60 the table 49 must be raised until it tightly presses the hand 102 against the drum 10. The band is then, by means of the cutter 77 cut between them across its width. When the table 49 is moved upward, the collars 61 reach the position indicated by the dotted lines (Fig. 3) and raise the guide 63 together with the spring 71 and the small rollers 75 without their leaving the slit 76. When the lever 66 has been moved upward by means of the crank 68 the small rollers 75 are raised out of the slit 76 over the table 49 and catch the end of the band and cause it to adhere to the drum 10 by the action of the spring. The drum can be heated so as to insure the insulating material to be applied to the band remaining hot and adhere. After the band has been cut and the free end of it has been made to adhere to the drum, the small rollers 75 may be lowered by means of the crank 68 so that they may re-enter the slit 76 of the table. The latter is then by means of spur wheels 57 rack 55 and the chain gear 99, 60 and 100 brought to the lower position by the rotation of the hand wheel 98. The drum 10 by means of the belt 31 is then made to rotate by the motor connected with it when the transmission gear is brought into operation while simultaneously by means of the rod 109 the brake band 105 is made to act with greater intensity and by means of the rod 109 the lever 108 is displaced and allows the weight 106 to descend. Then the band 102 is rolled up around the drum 10 which however is at the same time compelled to approach the supporting rollers 32 and 33 together with the support 3 inasmuch as the length of the band already unrolled from the roller 104 is reduced to an extent equal to the length wound around the drum. When the drum together with the band wound around it comes in contact with the rollers 32 and 33 (Fig. 1) then the brake 105 is again released owing to the raising of the weight 106 by the lever 108 and the pulling rod 109. By regulating the brake power during the motion of the band on the transferring roller 79 the pressure of the drum against the rollers 32 and 33 when the band is being wound up, is altered and at the same time by the alteration of the temperature in said rollers the thickness of the coat of insulating substance which is to be retained on the band may be varied as desired.

Upon the displacement of the support 3 from its central position against the rollers 32 and 33 the rail 20 together with the pro-

jection 18 occupies the right hand extreme position and is not actuated by the catch 17 so that the roller 93 also remains in the highest position shown in Fig. 1. When the 5 rotation of the drum 10 is continued the band 102 is wound around it after the liquid insulating material has been steadily transferred to it. The winding continues until the desired thickness of the tube has been 10 obtained. At that moment the roller 28 comes in contact with the circumference of the wound-up tubing, is raised and displaces the lever 27 upward, so that the latter is no longer in contact with the contact piece 30 15 whereby the motive power of the drum 10 is affected in the manner previously explained. The bearings 9 are then opened, the halves 9^b of the same are turned down and the support 3 is then together with the drum carrying the winding displaced by the action 20 of the hand crank 6 until the ends of the drum are introduced into the bearings 34 which have been previously opened to receive them. Then the bearings 34 are tightened up by means of the screw 45 so as to hold the drum. The vacant support 3 in which a new drum is introduced is moved back by hand or by means of the crank 6 and reaches its central position again above 25 the table 49. The table is then again raised as before and the band which adheres between the latter and the new drum is cut off between the cutters 77. When the wound up drum leaves the support 3 the spring 29 tends to again drive the lever 27 against the contact piece 30. The latter is therefore held by a wedge or other similar device of 30 non-conducting material, which is not removed until the support 3 again occupies its 35 central position. The result is that the circuit by the interruption of which the coupling of the transmission gear between the spindle and the motor is released remains unbroken until the winding of the end of 40 the band around the drum begins again.

The drum with the winding and carried by the bearings 34 is now further rotated in the manner hereinbefore stated by means of the pulley 16 operated by hand, when the 45 part of the band hanging on the wound-up spindle is caught and made to adhere to the drum. The necessary pressure for this purpose is obtained by the board 48 which by the action of overweight comes to rest upon the circumference of the wound-up tubing. The latter is then together with the drum removed from the bearings 34 previously 50 opened and then the drum is heated from the inside for the purpose of removing the tubing from the drum. Such removal is 55 easy, as the insulating substance attached to the drum then melts. The end of the band 60 held between the new drum and the table 49 is made to adhere to and wind

around the said drum in the same way as 65 before mentioned, which for this purpose after the removal of the insulator wedge inserted between lever 27 and the contact piece 30 is again worked by motor, when at the same time the brake band 105 is more powerfully applied. The collar 19 on the rail 20 70 must be fixed in such manner that said collar should be seized by the catch 17 and the rail 20 should be displaced so soon as the drum reaches the bearings 34 and the band 75 102 is stationary. By means of the rail 20, which is displaced to the left the lever 94 and the roller 93 are caught and moved in the same direction. Then the guiding roller 93 goes down and allows the band 102 to 80 move away from the roller 79 which continues to rotate without however actuating the band.

Claims:

1. A tube making machine comprising a 85 frame, a bearing slidable thereon, a drum mounted in the bearing and adapted to be encompassed by a tube-forming band, a transfer roller for conveying a plastic substance to the band, a guide roller arranged 90 in proximity to the transfer roller, and means actuated by the bearing for projecting the guide roller against the band.

2. A tube making machine comprising a 95 frame, a bearing slidable thereon, a catch on the bearing, a bar also slidable in the frame, a pair of adjustable stops on the bar that are adapted to be engaged by the catch, a transfer roller for conveying a plastic substance to the band, a guide roller arranged 100 in proximity to the transfer roller and adapted to engage the band, and means for operatively connecting the bar to the guide roller.

3. A tube making machine comprising a 105 frame, a drum mounted thereon and adapted to be encompassed by a tube-forming band, means for applying a plastic substance to said band, a vertically reciprocable table, a cutter mounted on said table adapted to 110 sever the band, and a plurality of spring-controlled rollers also carried by the table and adapted to press the end of the severed band against the drum.

4. A tube making machine comprising a 115 frame, a bearing slidable thereon, a drum hung in the bearing and adapted to be encompassed by a tube-forming band, means for applying a plastic substance to the band, means actuated by the bearing for controlling the supply of said substance, means for severing the band, means for pressing the end of the severed band against the drum, and heating rollers arranged in the path of the drum and adapted to engage the band. 120

5. A tube making machine comprising a 125 frame, a bearing slidable thereon, a drum hung in the bearing and adapted to be en-

6
compassed by a tube-forming band, a transfer roller for applying a plastic substance to the band, a guide roller adapted to engage the band and operable by the bearing, a vertically reciprocable table, a cutter on said table adapted to sever the band, a plurality of spring-controlled rollers also carried by the table and adapted to press the

end of the severed band against the drum, and heating rollers arranged in the path of the drum and adapted to engage the band.
